C. F. YARDLEY

RAIL ANCHOR

Original Filed July 8, 1921

Charles F. Yardley Inventor
Barnett Truman Attorney

UNITED STATES PATENT OFFICE.

CHARLES F. YARDLEY, OF LARCHMONT, NEW YORK.

RAIL ANCHOR.

Original application filed July 8, 1921, Serial No. 483,179. Divided and this application filed July 15, 1922. Serial No. 575,252.

To all whom it may concern:

Be it known that I, CHARLES F. YARDLEY, a citizen of the United States, residing at Larchmont, in the county of Westchester 5 and State of New York, have invented certain new and useful Improvements in Rail Anchors, of which the following is a specification.

My invention relates to rail anchor devices, 10 and has for its principal object the provision of a new and improved one-piece rail anchor device which may be easily applied to or removed from a rail, which will maintain its initial grip on the rail by spring 15 pressure and which will increase its grip on the rail during the presence of a creeping pressure on the rail.

A more specific object of the invention is to provide certain improvements in the type 20 of rail anchor described and claimed in my United States Letters Patent No. 1,201,415 dated October 17th, 1916.

A further and more specific object is to provide an improved rail anchor of a one-piece construction adapted to grip a rail with spring pressure, in which a spring tongue bearing at its end only against the upper surface of the rail base, maintains 25 said spring grip.

30 The invention consists in the provision of a new and improved anchor constructed as hereinafter described and claimed for carrying out the above stated objects, and such other objects as will appear from the following description.

The invention is illustrated in a preferred embodiment in the accompanying drawing, wherein:

Fig. 1 is a plan view of a rail anchor constructed in accordance with my invention, the device being shown in its operative position in full lines and in its partially applied position in dot and dash lines.

Fig. 2 is a view in elevation of the anchor device shown in Fig. 1, the base flange of the rail being shown in cross-section.

Fig. 3 is a view in perspective of the rail anchor device shown in the preceding figures, and

50 Fig. 4 is a view of one end of a blank from which the anchor shown in the preceding figures is formed.

Like characters of reference designate like parts in the several figures of the drawing.

55 Referring to the drawing, wherein I have

shown my improved anchor device as comprising a body portion 10, cut away as indicated at 11, to provide a recess for receiving the base portion 12 of a rail, a tie abutting portion 13 adapted to bear, adjacent one edge of the rail base, against one of the vertical faces of the cross tie 14, and a spring tongue portion 15 which projects over one edge of the rail base and bears against the upper surface thereof. The configuration 60 of the recess 11 provides a jaw portion having a vertical edge 16 for engaging one of the base flanges of the rail and a lip 17 which bears against the upper surface of said base flange. The vertical edge 18 of the other 65 end of the recess 11 provides means for engaging the vertical surface of the other base flange of the rail. The distance between the vertical edges 16 and 18 of the recess 11 is, 70 preferably, sufficient to permit the anchor to be applied to rails, the base flanges of which, due to the wearing away of the rolls, with which they are made, are slightly wider than the bases of perfectly formed rails. Any clearance between the edges of the rail 75 base and the vertical edges 16 and 18 of the anchor will be taken up by shifting of the anchor to a diagonal position across the rail base. In order to minimize the distance between the vertical edges 16 and 18 of the recess 11, without making the application of the anchor more difficult, and without sacrificing the desired strength of the spring tongue 15, adjacent the edge 18, the edge 18 80 of the recess is preferably tapered outwardly, as shown at 19, from a point adjacent the upper edge of the rail base, so as to provide the necessary clearance to permit the edges 16, 18 to be engaged with the rail base. The tie abutting portion 13 of the anchor consists 85 of a straight "post portion" 20 and an angularly disposed foot 21. The post portion 20 is, preferably, straight and converges with the adjacent edge of the rail base in a direction toward the tie, and the angularly 90 disposed foot 21 projects under the rail base and engages with the tie at a point near the edge of the rail base when the anchor is in its applied position. The upper edge 22 of the tie abutting foot is preferably in 95 alignment with the upper edge of the body portion of the anchor so that it will bear against the under surface of the rail base when the anchor is in its applied position. The tie abutting surface of the foot 21 is 100 105 110

formed, preferably, curved, so as to confine its engagement with the tie to a point adjacent the edge of the rail base, thereby providing a relatively wide bearing surface, 5 and at the same time avoiding contact with the tie at points, for example, near the center of the rail, likely to resist the tendency of the anchor to assume a slight diagonal position across the rail base during 10 the presence of a creeping pressure on the rail.

The spring tongue portion 15 of the anchor is bent on line 23 of the blank (Fig. 4) to project toward the tie 14 and stands 15 at an angle to the body portion, so that the distance between the vertical edge 16 of the jaw portion 24 and the end 25 of the tongue will normally be less than the width of the rail base to which the anchor is to be applied. 20 The anchor is preferably, so formed that the spring tongue 15 will bear at its end 25 only against the upper surface of the rail base. An engagement of this character is obtained by so forming the lower edge 26 25 of the tongue that it will stand at an angle to the inclined surface of the rail base when the anchor is in its rail gripping position. In the drawing I have shown the said lower edge of the tongue 15 disposed a short distance 30 above the upper edge of the body of the anchor and being parallel with the said upper edge of the body before the tongue is bent to its angular position.

The upper edge of the tongue is tapered 35 downward toward its end, preferably on a straight line, to provide a cam surface 27 which facilitates the application of the device to a rail by forcing the tongue portion outwardly from the edge of the rail base 40 when this end of the anchor is elevated until it clears the upper edge thereof, whereupon it will snap over the upper surface of the base.

In applying the anchor to a rail, the jaw 45 portion 24 is hooked over one edge of a rail base with the tie abutting foot 21 adjacent the tie 14. In this position the end of the spring tongue 15 extends under the rail base and the anchor assumes a general position, 50 substantially as shown in dot and dash lines in Fig. 1. The tongue end of the anchor may then be elevated by the use of a suitable implement (not shown) to bring the vertical shoulder 18 of the recess 11 in engagement 55 with the edge of the rail base. The inclined edge 27 of the tongue bears against the edge of the rail and functions as a cam to force the tongue outwardly until the tongue clears the upper edge of the rail base, whereupon 60 it will snap over the edge of the rail base and exert a lateral spring pressure against the inclined surface thereof. In addition to the lateral spring pressure of the tongue on the rail base, a vertical pressure is produced 65 by reason of a torsional strain to which the

body of the anchor is subjected during the application of the device. When the anchor is applied to its initial position, it will normally be at an angle to the length of the rail, as shown in the dot and dash lines, from 70 which position it may be driven to its operative position, so as to effect a firm shackle hold on the opposite edges of the rail base. The spring action of the tongue and the torsional strain of the body portion operate to 75 support the tie abutting foot 21 in its proper position against the under surface of the rail base.

This application is a division of my co-pending application Serial No. 483,179, filed 80 July 8, 1921.

Having described my invention, what I claim is:

1. A rail anchor comprising a rail base embracing member formed with means for 85 engaging opposite edges of said base, and a spring tongue, the lower edge of which stands at an angle to the inclined upper surface of said base and bears at its extremity against said surface when the anchor is in 90 its applied position.

2. A rail anchor comprising a rail base engaging member formed at one end with a tie-abutment and terminating at the other end in a spring-tongue adapted to bear at 95 its end only against the inclined upper surface of said rail base.

3. A rail anchor comprising a rail base engaging member formed at one end with a tie abutment and terminating at the other 100 end in a spring tongue extending diagonally across the upper surface of the rail base and adapted to bear at its extremity only against said upper surface.

4. A one-piece rail anchor comprising a 105 rail base embracing member formed at one end with a jaw for engaging one edge of a rail base, and with a tie abutting portion, comprising a rigid post portion which converges with the edge of the rail base in a 110 direction toward a tie and terminates in an angularly disposed flange adapted to bear against said tie, and formed at the other end with a shoulder for engaging the other edge of said rail base and with a spring 115 tongue adapted to bear at its end only against the upper surface of said base.

5. A one-piece rail anchor device comprising a rail base embracing member formed at one end with a jaw for engaging one edge 120 of a rail base, and with a tie abutment adapted to bear against a cross tie, and formed at the other end with a shoulder for engaging the opposite edge of said rail base and with a tongue adapted to snap over 125 the upper surface of the rail base, so as to exert a torsional strain on said body portion, said tongue being formed to bear at its end only against the upper surface of said rail base.

6. A one-piece rail anchor comprising a body formed at one end with a jaw having a lip adapted to engage the upper surface of a rail base at one edge thereof and with a forwardly projecting portion providing a tie abutment and formed at the other end with a shoulder for engaging the opposite edge of said rail base and with a spring tongue adapted to snap over and bear at 10 its end only against the upper surface of said rail base; said tie abutment being formed to confine its engagement with the tie to a point adjacent the edge of the rail base and said tongue and body being so 15 formed as to produce a torsional strain in the latter when the device is applied to a rail.

7. A one-piece rail anchor comprising a body portion formed with a jaw and a shoulder for engaging the opposite edges of a rail base and bent at one end to provide a tie abutment to engage a tie adjacent one edge of the rail and formed at the other end with a spring tongue adapted to snap 20

over and bear at its extremity only against the upper surface of the opposite edge of said base; the shoulder portion adjacent said spring tongue being formed with an outwardly tapered edge for the purpose described.

8. A rail anchor comprising a rail base embracing member formed with a jaw and a shoulder for engaging opposite edges of said base, and formed at one end with a tie abutment and at the other end with a spring tongue which extends diagonally across and bears upon said upper surface of said rail base; the upper edge of said tongue being formed with a downwardly tapered portion for the purpose described, and the lower edge of said tongue being formed substantially parallel with the upper edge of said body portion so as to confine the engagement of said tongue with the upper surface of the rail base to the outer end of said tongue.

CHARLES F. YARDLEY.
